UNITED STATES PATENT OFFICE.

PETER SIVERTSEN, OF NEW YORK, N. Y.

SLICING MACHINE.

Application filed April 18, 1922. Serial No. 555,034.

To all whom it may concern:

Be it known that I, PETER SIVERTSEN, a subject of the King of Norway, and residing in the city of New York, county of Bronx, and State of New York, have invented certain new and useful Improvements in Slicing Machines, of which the following is a specification.

My invention relates to slicing machines and their appurtenances and has more particular reference to an arrangement for facilitating the machine slicing of objects at angles other than the conventional machine cut, that is, at angles other than at right angles to the longitudinal axis of the object. More especially the present invention is adapted for the slicing of bologna and similarly dimensioned objects. Bologna is customarily cut with a knife and generally at an angle of about forty five degrees to the longitudinal axis of the object, primarily because most of the machines now in use do not afford the necessary convenience of operation to make it worth while using a machine to slice this type of object, and this applies even when a cut at right angles to the longitudinal axis of the object is to be made. A type of machine which is admirably suited to the slicing of this type of object, particularly when the angle of cut is at right angles to the longitudinal axis of the object, is the type of machine disclosed in my prior copending application filed August 22, 1919, under Serial Number 319,059 in which a specific example of a slicing machine is shown comprehending an inclined chute, (V shaped in cross section) down which the object slides by its own weight. While this machine is suited to the cutting of slices at right angles to the longitudinal axis of the object, nevertheless by holding the object at an angle to the plane of the cutting mechanism on one of the faces of said chute, objects may be sliced at an angle to their longitudinal axis. While this manner of holding the object effects the major purpose in a measure, it does not quite afford the necessary support nor does it enable the slices to be as accurately uniformly and expeditiously cut as does my present invention, which provides an arrangement which affords adequate support for the object and at the same time ensures uniform angularity of cut. One example of

the invention which effects this end comprehends an auxiliary device applied to the type of machine disclosed in my above mentioned copending application. Another example of my invention for accomplishing this result comprehends an arrangement for changing the angular relation of the feed-way with respect to the plane of the knife, so as to change the direction of feed with respect to the latter element. While I am aware that a construction is shown in the United States patent to Graff numbered 667,364 and dated February 5, 1901, which involves a chute rectangular in cross section, the vertical angular inclination of which may be changed with respect to the plane of the knife, the construction is inferior to my present invention primarily in the use of the inconvenient clamping elements to feed the object, and the inconvenient movable knife.

Broadly stated therefore, one phase of my invention among others, comprehends a cutting mechanism and gravity feeding means for feeding the object to be sliced to the cutting mechanism, the direction of feed relatively to the plane of the cutting mechanism being variable.

While two embodiments of the invention are disclosed, it is to be understood that these embodiments merely serve as illustrations of the underlying principle of the invention, and are not intended as limiting the invention to the specific forms disclosed in the drawings, these embodiments together with the description thereof being of such a nature as will enable those skilled in the art to practice the invention and to devise other equivalent modifications thereof without departing from the underlying principle of the invention.

In said drawings:—

Fig. 1 is a side elevation of one embodiment of the invention;

Fig. 2 is a top plan view of the invention shown in Fig. 1;

Fig. 3 is a section of Fig. 2 on the line 3—3.

Fig. 4 is a side elevation of another modification of the invention, partly fragmentary;

Fig. 5 is a fragmentary end view of a modification of some of the elements shown in Fig. 4;

Fig. 6 is an end elevation of the modification shown in Fig. 4, also partly fragmentary, and

Fig. 7 is a section of Fig. 6 on the line 5 7-7.

Continuing now by way of a more detailed description, a cutting mechanism indicated in its entirety by A comprehends a guard casing A' for the knife A'' which 10 rotates within said casing. The foregoing cutting mechanism co-operates with a tray B having a suitable mechanism controlled by the handle B' for changing the elevation thereof with respect to the knife edge A'' 15 to regulate the thickness of the slices. A reciprocating gravity feed holder specifically taking the form of an inclined chute in the illustrated embodiment, is supported in a sliding bracket C' arranged to reciprocate on the horizontal guide rods C''. It is to be understood that a single rod might be used instead of the double rods if means were provided for preventing the sliding carriage from turning around the single 20 rod. The foregoing elements are substantially similar to the corresponding elements shown and described in my co-pending application above referred to, and have no bearing on the present invention other than 25 affording a specific application of the invention. My present invention, shown in Figs. 1, 2 and 3 has more special reference to the guide strip D, which is adapted to be attached to the inclined chute C. This 30 guide strip preferably takes the form of an upstanding flange D and is of sufficient width to afford an adequate abutment for the object to be sliced—in general about an inch and a half for the smaller sized bologna. While the present invention is more 35 particularly designed for the purpose of slicing bologna and the like, nevertheless, it is evident that the guide strip D might be used with larger objects when it is desired 40 to slice the object at an angle other than that afforded by the chute C, and this might entail widening the strip D as will be readily understood. In the embodiment shown 45 in the drawings, this guide strip may be and preferably is formed with a slotted flange D'' preferably having its plane at right angles to the plane of the upstanding flange D' to afford a secure footing for the device. Obviously, however, it may under 50 certain circumstances be desirable to change the angular inclination of the upstanding flange D' with respect to the plane of the face of the chute to which this attachment 55 is applied, in which event the angular relations of the plane of the footing flange and the upstanding flange will be suitably altered.

In order to secure this attachment to the 60 face of the chute C, one end of the member D may be and preferably is provided

with a downwardly projecting pin 10 preferably bayonet shaped, and adapted to enter a recess 11 conveniently drilled in one face of the chute C, the co-operation of the pin 10 with the recess 11 affording the necessary immobility to one end of the strip D relatively to the chute. While the hole 11 is preferably drilled as above indicated, it is obvious that a rectangular shaped recess engaged by a bayonet shaped pin having a 75 rectangular shank may under certain circumstances be found desirable when it is desired to prevent the member D from rotating about the pin 10 as an axis. Obviously other methods of securing the end of the element D to the face of the tray may be used. Irrespective of the manner of attaching the end of the element D to the face of the tray, it is desirable to provide additional 80 elements for securing some other portion of the element D to the tray, and this is particularly true when a drilled hole is used to receive the pin 10. To this end a sliding block having suitable locking means is 85 preferably arranged to slide on one edge of the chute C. In the specific embodiment of the invention illustrated, the slot in the flange D'' is indicated by 12, while the block is indicated by 13. The means for locking 90 this block in position specifically takes the form of a set screw 14, adapted to bear against the rear face of the chute C. Instead of the set screw 14, obviously a spring friction element or the like might be located between one of the faces of the block 95 13 and the face of the chute C to hold the block in frictional engagement therewith, thereby obviating the required adjustment of the screw 14 in case it is employed. The arrangement is designed to normally 100 provide a cut of about 45° to the longitudinal axis of the object. Under some circumstances, however, it may be found desirable to change the relative inclination of the element D with respect to the plane of the 105 knife to afford other angular cuts in the object to be sliced than a 45° cut. To this end the slot 12 of the flange D'' is engaged by a pin 15 secured to the inner face of the block 13. Evidently the pin and slot arrangement just described affords means for 110 keeping the block in such position contiguous to the edge of the chute that the set screw 14 may be utilized in clamping the block to the chute C at all angles of member 115 D within the designed limits. Obviously various equivalents of the pin and slot arrangement may be utilized. In view of the fact that some of the objects to be sliced for which the present attachment is primarily 120 designed are considerably longer than the chute C, it has been found desirable although not essential to extend the upstanding flange D' a considerable distance beyond the chute. In order to afford a sup- 125 130

port for the end of the object remote from the knife, a flange E is arranged preferably at right angles to the upstanding flange D' and preferably lying in the same plane as the particular face of the chute C to which the entire attachment is secured, although the flange E might be concave to better receive the bologna. It is quite evident that the flange E not only serves to support the end of the object projecting beyond the edge of the chute C, but also serves as a stop to limit counter clockwise movement of the element D (when viewed as in Fig. 2) when the flanges E and D' are integrally formed as shown in the drawings. It is evident, however, that the flange E might be arranged to slide in a suitable groove in the flange D' and by connecting the end of this sliding flange to the block 13, the flange might be kept abutting against the edge of the chute C at all times.

The modification shown in Figs. 4, 5, 6 and 7 disclose an arrangement which effects substantially the same result effected by the guide strip D in the above described modification. In this modification the change in the inclination of the object with respect to the plane of the knife is effected by arranging the chute F so as to swing in two directions, thereby achieving its universal adjustability. In this modification, a rotary knife G similar to the rotary knife A', a tray H for regulating the thickness of the slices similar to the regulating tray B, and a chute F similar in configuration to the chute C, although not held in a permanent position with respect to bracket K as is the chute described in the previous modification, are provided. Chute F instead of being supported in bifurcated brackets as is the case in the construction shown in Fig. 1, is pivotally supported at its lower opposite corners preferably by threaded trunnions J projecting from the chute F engaging bearings formed at the ends of the arms 16 and 17. The trunnions may carry clamping screws J' to clamp the bearings formed on the end of the arms 16 and 17 and the trunnions together, to prevent relative motion of the chute F and hold it at a predetermined angle. The arm 16 is preferably flared in the manner shown in Fig. 4 so as to provide a closure between the lower edge of the chute C and the regulating tray K so that when the chute is elevated for example to the position shown by dotted lines in Fig. 6, sufficient abutment will be provided for the lower end of the object which is to be sliced to prevent its lateral displacement. Preferably the arms 16 and 17 are cast, or otherwise formed integrally with each other, arm 16 having a pin holder 18 recessed at 19, the recess being adapted to receive and hold a journal pin 20 the pro-

jecting end of which enters bearings 21 formed in the bracket K. The longitudinal axis of this journal pin is arranged parallel to the lower edge of one of the faces of the chute F so that as the latter is swung around the journal pin 20, the lower edge of one of the faces of the trays F remains relatively stationary while the edge of the other face of the chute F rises from the plane of the knife. In order to lock the journal pin 19 to the bracket K, a set screw actuated by means of a handle 22 is arranged to lock the pin 19 to bearing 21. Instead of the clamping screws J' shown in Figs. 4 and 6, for locking the chute F in predetermined position, it is quite evident that the arms 16 and 17 might be flared sharply near their junction to form an upstanding bracket M as shown in Fig. 5, thereby affording additional support to the chute F when in its normal position as indicated by full lines in Fig. 6, and providing means through an elevating screw N for tilting the chute say to the position shown by dotted lines in Fig. 6. Since the elevating screw N will hold the chute F in predetermined position obviously the clamping screws J' may be dispensed with when this elevating screw is used.

The manner of utilizing the present invention and its mode of operation is as follows:

The gravity feed chutes C and F are arranged to reciprocate on the guide rods C''. When it is desired to utilize the modification of the invention shown in Figs. 1 and 2, the guide strip D' is moved to the desired angular position, which may be readily ascertained from a suitable scale provided on the edge of the chute, and the object to be sliced is laid on the face of the chute adjacent to the guide strip D'. The object may be guided by the finger of the operator, although obviously an arrangement for holding the object may be readily provided as for example a V-shaped chute similar to the chute C but on a small scale might be used to feed the object, and this small chute might be formed by using the flange D' as one of the faces of said chute, or an auxiliary chute entirely independent of the chute C might be provided. The flange D' having been moved to the desired position as above indicated, the set screw 14 is clamped to hold the flange D' in desired position.

In the modification shown in Figs. 4, 5 and 6, the chute F is swung about the trunnions J to any desired angular position, the degree of inclination being read from a suitable pointer and scale arrangement, and the object to be sliced placed in the chute and the bracket K reciprocated on the guide rods C'', so that as the chute F is moved back and forth relatively to the rotary

knife G, which is driven by any suitable mechanism, the desired angular cut is effected. Similarly by rotating handle 22 to loosen the set screw the chute F may be 5 swung about the pin.

While two modifications of the invention have been disclosed, and various equivalents have been mentioned in the course of the description, it is not to be understood that these 10 are the only modifications or equivalents, but are merely mentioned for the purpose of affording a clear understanding of the underlying principle of the invention.

Having thus revealed my invention, I 15 claim as new, and desire to secure the following combinations and subcombinations of elements or equivalents thereto by Letters Patent of the United States:

1. A slicing machine combining a cutting 20 mechanism and reciprocative gravity feeding means for feeding the object to be sliced to said cutting mechanism, the direction of feed being variable relatively to the direction of the reciprocation.

2. A slicing machine combining a cutting 25 mechanism, a tray for regulating the thickness of the slices, and reciprocative feeding means for feeding the object to be sliced to said cutting mechanism, the direction of 30 feeding being variable relatively to the direction of the reciprocation.

3. A slicing machine combining a cutting 35 mechanism and reciprocative feeding means for feeding the object to be sliced to said cutting mechanism adapted to be moved relatively to said cutting mechanism, the direction of feed being variable relatively to the direction of the reciprocation and the feeding means and the cutting mechanism being 40 movable relatively to each other.

4. A slicing machine combining a cutting 45 mechanism and feeding means for feeding the object to be sliced to said cutting mechanism, the direction of feed of said feeding means being universally variable relatively to the plane of the cutting mechanism.

5. A slicing machine combining a cutting 50 mechanism and reciprocative feeding means comprising a feed chute having a V shaped cross section and means for varying the direction of feed of said feed chute.

6. A slicing machine combining a rotary 55 cutting mechanism, self feeding means comprising a carrier for feeding the object to be sliced to said cutting mechanism, and a guide strip against which the object to be sliced is adapted to rest to feed the object, the guide strip being movable relatively to the plane of the cutting mechanism and the carrier.

7. A slicing machine combining a cutting 60 mechanism and a reciprocative gravity feed chute for feeding the object to be sliced to said cutting mechanism, the inclination of said chute relatively to the plane of the cut-

ting mechanism and to the direction of reciprocation being variable.

8. A slicing machine combining a cutting 70 mechanism, an inclined chute, and means for pivotally supporting said chute, said supporting means and chute being reciprocative past the cutting mechanism.

9. A slicing machine combining a cutting 75 mechanism, a chute, a reciprocating bracket, and a pivotal connection between said chute and bracket, said connection being arranged so that one edge of the chute remains substantially stationary on movement of the chute about said connection.

10. A slicing machine combining a cutting 80 mechanism, a chute, means to hold said chute so that it may be moved back and forth with respect to the cutting mechanism and pivotal connections between said chute and holding means to permit universal change of direction of said chute with respect to the plane of the cutting knife.

11. A slicing machine combining a cutting 85 mechanism, an inclined chute having a V shaped cross section, means for holding said 90 chute so that it may be moved back and forth past the knife and connections between the chute and holding means to permit the chute to be universally inclined with respect to the plane of the cutting mechanism.

12. An auxiliary device for slicing machines combining a guide strip, means for pivotally attaching one end of the guide strip to a slicing machine part and means for holding the other end in position on said machine part and comprising a slidible block.

13. A slicing machine combining a rotary 95 knife and reciprocative gravity feeding means for feeding the object to be sliced to said rotary knife, the direction of feed being variable relatively to the plane of the rotary knife.

14. A slicing machine combining a rotary 100 knife, a tray for regulating the thickness of the slices, and means movable relatively to the tray for feeding the object to be sliced to said rotary knife, the direction of feed being variable relatively to the plane of the rotary knife.

15. A slicing machine combining a rotary 115 knife and reciprocative means for feeding the object to be sliced to said rotary knife, the direction of feed being variable relatively to the plane of the rotary knife and to the direction of reciprocation of said means, and the feeding means and the rotary knife being movable relatively to each other.

16. A slicing machine combining a rotary 120 knife and feeding means for feeding the object to be sliced to said rotary knife, the direction of feed of said feeding means being universally variable relatively to the plane of the rotary knife.

17. A slicing machine combining a rotary 130 knife and reciprocative feeding means com-

prising a feed chute having a V shaped cross section and means for varying the direction of feed of said feed chute.

18. A slicing machine combining a rotary knife, feeding means comprising a feed chute for feeding the object to be sliced to said rotary knife, and a guide strip against which the object to be sliced is adapted to

rest to feed the object, the guide strip being inclinable relatively to the plane of the rotary knife.

Signed at the city of New York, in the county of New York and State of New York, this 6 day of December, A. D. 1921.

PETER SIVERTSEN.
